United States Patent Office

Des. 182,942
Patented May 27, 1958

182,942

HANDLE CAP

Benjamin T. Wrubel, Providence, R. I., assignor to Miller Electric Co., Pawtucket, R. I., a corporation of Rhode Island

Application September 13, 1956, Serial No. 42,918

Term of patent 14 years

(Cl. D26—1)

Fig. 1

Fig. 2

The dominant features of my new design are shown in solid lines in the drawing.

I claim:

The ornamental design for a handle cap, as shown and described.
